ART OF MAKING ONE-PIECE WINDOW ENVELOPES

Filed July 1, 1921

Inventor:
W. E. Swift
By G. H. Kennedy,
Attorney.

UNITED STATES PATENT OFFICE.

WILLARD E. SWIFT, OF WORCESTER, MASSACHUSETTS, ASSIGNOR TO UNITED STATES ENVELOPE COMPANY, OF SPRINGFIELD, MASSACHUSETTS, A CORPORATION OF MAINE.

ART OF MAKING ONE-PIECE WINDOW ENVELOPES.

Application filed July 1, 1921. Serial No. 481,858.

To all whom it may concern:

Be it known that I, WILLARD E. SWIFT, a citizen of the United States, residing at Worcester, in the county of Worcester and

5 Commonwealth of Massachusetts, have invented a new and useful Improvement in the Art of Making One-Piece Window Envelopes, of which the following, together with the accompanying drawings, is a specification.

10 The present invention relates to the manufacture of window envelopes of the one piece type, viz, those in which an integral portion of the face of the envelope is rendered transparent or semi-transparent, for the disclosure through same of the address on the enclosure. Such window envelopes are to be distinguished from the two piece type, wherein a separate transparent patch is secured, by adhesive or the like, over an opening cut in the face of the envelope.

15 The process of making a one piece window envelope involves, among other things, the treatment of a portion of the envelope blank with a suitable penetrating varnish which has the faculty of so reacting on the fibers of the paper as to partially destroy the opaque character of the same. Such varnish is applied, preferably, to the inside surface 20 of the flat or extended envelope blank, so that when said blank is folded, the outer surface of the envelope is devoid of the stickiness that the use of such a varnish inevitably entails. Heretofore in the manufacture of one piece window envelopes, the application of the varnish, for the purpose 25 of producing a transparent or a semi-transparent window in the unfolded blank has been carried out as a separate, detached, and 30 independent step in the manufacture of such envelopes; after receiving their imprints of varnish, the blanks have to be removed separately from the imprinting mechanism and placed in trays, in such manner as to prevent their sticking together or smearing. The trays are then placed in an oven and 35 after the varnish has penetrated and has sufficiently dried the trays are removed and the blanks are assembled, by hand, into 40 stacks, in readiness for the subsequent folding operation. The manufacture of one piece window envelopes by the process above 45 described is wasteful of time, space and

material; moreover, it requires a large amount of special equipment, in the form 55 of drying trays and ovens, for production in large quantities.

5 The present invention involves the elimination of the above mentioned disadvantages and also of the consequent slow and laborious handling of the blanks, by making the process of their manufacture continuous,—the successive operations of their treatment with the penetrating varnish, their heating, 60 to promote penetration, and drying, and 65 their stacking, preparatory to folding, being accomplished automatically, by a series of related steps. The mode or manner in which such continuous manufacture is obtained, will be fully set forth in the following 70 description, reference being had to the accompanying drawings, wherein

Figure 1 is a sectional representation of the connected instrumentalities for successively conveying, imprinting, drying and 75 stacking the blanks, in accordance with the invention.

Figure 2 is a perspective diagrammatic showing of the successive steps in the treatment of the blanks.

80 Like reference characters refer to like parts in the different figures.

As indicated at the left hand side of Fig. 1, a suitable stack of untreated blanks, represented by the numeral 1, is disposed in operative relation to a suction of other pick-up mechanism 2, the blanks being uniformly arranged in the stack 1 with their inside surfaces uppermost. The pick-up mechanism 2 may be of any type, well known in 85 the art, and adapted to seize successive topmost blanks of the stack 1, and present them, flatwise, to a suitable feeding mechanism 3, here shown as consisting of horizontal sets of endless belts or bands 4, 4, 90 which run on suitable rollers 5, 5. Each blank as conveyed flatwise on the feeding mechanism 3, is adapted, before its delivery from said feeding mechanism to be definitely centered and squared; any suitable means 95 may be employed for this purpose, as for instance a set of gaging stops 6 which are moved by a cam 6' intermittently, into and out of the path of the successively fed blanks.

100 Disposed in relation to receive the indi-

vidual blanks from the feeding mechanism 3, is a cylinder 7, adapted to rotate continuously in a clockwise direction, and provided with a suitable gripper 8, the latter adapted 5 to close over the advancing edge of the blank as it is presented to said cylinder, and adapted to open, to release said edge, when the blank has been moved by said cylinder into a position substantially tangential to a 10 second cylinder 9. This cylinder 9 constitutes a bed plate, being suitably covered for this purpose, and it is also provided with a gripper 10, the latter operating in synchronism with the gripper 8 of cylinder 7, 15 so that when said gripper 8 is opened to release the blank, the gripper 10 closes thereon and thus secures the transfer of the blank from the cylinder 7 to the cylinder 9, the latter rotating in a counterclockwise direction. 20

It is to be noted that the blanks have their inside surfaces uppermost on the cylinder 7, but when transferred to the cylinder 9 their outside surfaces are uppermost. This affords opportunity for printing on the face 25 of the envelope a suitable margin to define the transparency, as indicated at 11, Fig. 2. Such printing, while the blank is supported on the bed plate afforded by cylinder 30 9, may be accomplished by the cooperation of a printing cylinder 12, the latter carrying a suitable oval or rectangular printing die 13 which receives its supply of ink, at each 35 revolution, from suitable transfer mechanism of well known form, here shown as composition rollers 14, 14, cooperating with a feed cylinder 15, the latter being supplied by a vibrating roller 16 from an ink fountain 17. These printing instrumentalities, 40 per se, form no part of the present invention, and hence need not be described in detail.

After each blank has received on its outer 45 surface the printed margin, it is carried by the cylinder 9 and gripper 10 into tangential relation to a third feed cylinder 18, the latter having a gripper 19 which closes on the forward edge of the blank as the latter is released by the gripper 10. The cylinder 50 18 acts as a bed plate for a die 20 on a varnish imprinting cylinder 21, the die 20 being of the size and shape suitable for imprinting an oval or rectangular window or transparency in the blank, as shown at 22, 55 Fig. 2. The operation of the several parts is so synchronized that the die 20 which receives at each revolution a supply of varnish from transfer rolls 23, 23, is brought into contact with the blank on cylinder 18 60 just as the printed impression 11 becomes tangent to the cylinder 21. The varnish penetrates the fibers of the paper, being prevented from spreading by the printed margin; thereafter said blank is transferred 65 to a final gripper cylinder 24, whose gripper

25 releases the blank as the latter approaches the plane of a horizontal conveying mechanism 26.

Said conveying mechanism 26 is shown here in the form of a pair of endless chains 70 27, 27, the latter providing suitable spaced pins or projections 28, 28, which move the flat blanks along suitable stationary bars or skids 29, 29. Chains 27, 27, pass over guide pulleys 30, 30, at each end of the conveying mechanism. Intermediate said guide pulleys the chains pass through an elongated heating chamber or oven 31, the latter providing any suitable heating means, such as steam, 75 gas, or electricity, for assisting the penetration and for evaporating the excess moisture in the varnish. The heating chamber 31 may be as long as required for this purpose, it being understood that the blanks are successively conveyed therethrough in a continuous manner by the conveying mechanism, so as to emerge from the right hand end of said heating chamber in a substantially dried condition. Chains 27, 27, deliver the blanks one by one, to gripping devices 90 32, 32, here shown as applied to an overhead band or belt 33; the movement of the latter causes the release of the gripper 32, by a cam 34, just as the blank is registered over a set of guide rods 35. Successive blanks pile up or collect in this way by gravity on a plate 36, in a uniform stack, and are thus in readiness, without any handling whatsoever for presentation to folding devices not shown, of any well known type. 100

I claim,

1. The improvement in the art of making one-piece envelopes which consists in printing window margins on the outer surface of successive blanks, applying a liquid transparentizing material to the inner surfaces of said blanks, within the space defined by said printed margins, moving said treated blanks successively, with their inner surfaces uppermost, through a heated chamber 105 to dry the same, and procuring their formation into a stack, by continuance of said movement beyond said chamber. 110

2. The combination with means for applying a liquid transparentizing substance to successively fed envelope blanks, of a travelling conveyor on which said treated blanks are successively deposited flatwise with their treated faces uppermost, a drying 115 chamber through which said travelling conveyor passes, and means operable to remove successive blanks from said conveyor, and by further movement thereof to assemble them into a stack or pile. 120

3. The herein described method of making one-piece window envelopes in a continuous manner, which consists in applying a liquid transparentizing substance to successively presented blanks, drying said 125 blanks, successively, by movement of the 130

same, one by one, through a heated chamber, and procuring the stacking of said blanks, by gravity, by continuance of said movement.

- 5 4. The combination with means for applying a liquid transparentizing substance to successively fed envelope blanks, of a travelling conveyor on which said treated blanks are successively deposited, a drying chamber through which said travelling conveyor passes, gripping means by which each blank is seized from above as it leaves said conveyor, and means for releasing said gripping means to permit the piling or stacking of said blanks by gravity. ¹⁰ ¹¹

Dated this 25th day of June, 1921.

WILLARD E. SWIFT.
